BOBBIN

Charles F. Beran, Tuckahoe, N. Y., assignor to
Celanese Corporation of America, a corporation
of Delaware

Application June 5, 1931, Serial No. 542,278

3 Claims. (Cl. 242—118)

My present invention relates to bobbins, spools and the like used in textile industries and more particularly to bobbins, spools and the like adapted for use in cap spinning operations. The 5 terms "bobbins" will be hereinafter used to designate spools and tubes as well as bobbins.

In the spinning of yarns of artificial filaments continuously with their production by the cap spinning method, the bobbins are rotated by a 10 suitable spindle construction at very high speeds, namely from 10,000 to 20,000 revolutions and more per minute. When a bobbin has been fully wound, it is removed from the whirl by an operative who immediately places a fresh bobbin 15 onto the whirl which continues its rapid rotation. In this latter operation the bobbin is subjected to especially hard usage for the bobbin is slammed against the rapidly revolving whirl and held against it by the operative until the 20 projections or shoulders on the whirl engage a suitable slot in the bobbin.

Cap spinning bobbins, as heretofore commonly constructed, comprised an integral wooden structure turned from a solid block of wood. These 25 wooden bobbins proved very unsatisfactory for due to the hard wear to which cap spinning bobbins are subjected, portions of the flanges frequently split off thus making it necessary to 30 discard them as being no longer fit for use.

Another factor which contributed to lower 35 considerably the efficiency and the life of these wooden bobbins was the ease, relatively speaking, with which these bobbins warped, cracked, split and became otherwise defective by reason of 40 deformations caused by changes in climatic conditions.

It is an object of this invention to provide an 45 improved bobbin structure which will be free from the above mentioned and other disadvantages and which will be especially simple in construction and durable and efficient in use.

Another object of my invention is the 50 provision in a bobbin of the type described of a replaceable bearing member which is adapted to receive substantially all the wear incident to the use of the bobbin and when too worn to be of any further utility may be readily removed and 55 placed by a new bearing member.

Other objects of this invention together with 55 certain details of construction and combinations of parts will be more particularly described in the specification and pointed out in the appended claims.

In the drawing:

Figure 1 is a perspective view of my improved bobbin;

Figure 2 is a vertical cross-sectional view of the same and

Figure 3 is a cross-sectional view taken on line 3—3 in Figure 2.

Like characters of reference indicate corresponding parts throughout the several views of the drawing.

Referring to the drawing wherein the preferred embodiment of my invention is set forth, the reference numeral 5 generally indicates a bobbin comprising flanges 6 and 7 formed integral with a core, or barrel, 8 upon which the yarn 70 is adapted to be wound. Within the core 8 and formed integral therewith are ribs 9. While but three of such ribs are shown, any desirable number may be used. The ribs are cut away, as is shown at 10, the construction being such that 75 the lower ends of the ribs converge upwardly and thus the ribs form guides as well as bearings for the whirl upon which the bobbin is adapted to rotate. The particular construction of the ribs, as shown in Figure 2, not only makes a 80 lighter bobbin structure but also provides a longer bearing for the spindle thereby causing the bobbin to sit more rigidly on the whirl.

The flange 7 is cut away at 11 to reduce the weight of the bobbin and is recessed at 12 to 85 form a seat 13 which is adapted to receive and retain as by a force fit a bearing member, or bushing, 14. The bushing is apertured at 15 to receive the whirl and is provided with a slot 16 which cooperates with the shoulders on the 90 whirl to rotate the bobbin, as is well understood in the art. The bushing is also provided with an integral annular member 17 which extends into the core 8 and acts as a bearing for the whirl. The flange 6 is provided with an annular groove 95 18 which further lightens the bobbin structure and is also adapted to receive and retain an identification ring, etc.

It will thus be seen that I have provided an 100 exceedingly durable bobbin structure which will greatly reduce the expense thereof, the barrel with its integral flanges being practically unbreakable and the bushing which receives substantially all the wear being readily replaceable when worn by a fresh bushing, thus extending 105 greatly the life of the barrel portion of the bobbin.

While my improved bobbin may be formed 110 from any suitable material which is not affected by climatic conditions, I prefer to make them

of any suitable metal as a better balanced bobbin is obtained by the use thereof. A balanced bobbin, as is well understood in the art, is substantially vibrationless thereby resulting in a better yarn package.

It is to be understood that the foregoing detailed description is given merely by way of illustration and that many variations may be made therein without departing from the spirit 10 of my invention.

Having described my invention, what I desire to secure by Letters Patent is:

1. A bobbin comprising a barrel having adjacent one end thereof a plurality of substantially rigid vertically extending ribs adapted to act as guiding and bearing members for a spindle and having at the other end a seat, and a bushing mounted in said seat, said bushing being adapted to be replaced when worn.

2. A bobbin comprising a barrel having adjacent one end thereof a plurality of substantially rigid vertically extending ribs adapted to act as guiding and bearing members for a spindle and having at the other end a seat, and a bushing mounted in said seat, said bushing being adapted to be replaced when worn.

3. A bobbin comprising a barrel having adjacent one end thereof a plurality of substantially rigid vertically extending ribs integral therewith adapted to act as guiding and bearing members for a spindle and having at the other end a seat, and a bushing mounted in said seat, said bushing being adapted to be replaced when worn.
